UNITED STATES PATENT OFFICE.

JACOB A. PAINTER, OF ARTHUR, ILLINOIS.

VICE.

SPECIFICATION forming part of Letters Patent No. 276,622, dated May 1, 1883.

Application filed January 8, 1883. (No model.)

To all whom it may concern:

Be it known that I, JACOB A. PAINTER, a resident of the town of Arthur, county of Moultrie, and State of Illinois, have invented 5 certain new and useful Improvements in Vises, of which the following is a specification.

My invention consists in a punch attachment for vises, constructed and arranged as will be hereinafter set forth.

10 In the drawings accompanying and forming a part of this specification, Figure 1 is an elevation of my devices. Fig. 2 is a cross-section of the vise-leg on dotted line *x* in Fig. 1. Fig. 3 is a vertical section of Fig. 2 on dotted line *y*. Figs. 4 and 5 are enlarged views of the punch. Fig. 6 is a face view of the die-block. Fig. 7 is the punch-tool, and Fig. 8 is a section through center of the die-block.

15 A is the vise; B, the punch; C, the shears; D, the support that secures the vise to the bench, and G is the die-block.

The punch in detail is as follows: *d* is a guide for the punch-tool *b*, secured to support D through slot *c* by bolt *e*. *e* is a spring that 20 acts as a support for the head of the punch-tool, and when the punch has been operated and the vise reopened carries said punch-tool to its original position. Punch-tool *b*, as shown in Fig. 7, is provided with a small 25 conical projection, *b'*, that fits in the mark of the center-punch, and secures a degree of accuracy which, from the location of the die-block and punch-tool, would otherwise be hardly attainable.

30 Die-block G is secured to the vise-leg in an adjustable manner by set-screw *i*, and when, with the metal to be punched resting on support D, the punch will not operate at the proper position vertically both die-block and punch 35 may be adjusted to conform to the metal slot *c* in the punch-guide *d*, being specially so designed. As shown in Fig. 8, the die-block

proper, *g*, is beveled to countersink in its frame, and by this construction a number of die-blocks having holes conforming to the different-sized punches may be kept on hand and readily interchanged.

Shears C are attached one to the cross-bar and one to the vise-leg, and, as will be readily seen, may be made in a variety of forms and secured in a variety of positions. Both shears and punch are operated by the vise, but in such a manner as not to interfere with its ordinary use, and from their form and position they are entirely out of the way, occupying a 55 space that heretofore has not been utilized.

In operation, as the vise-leg, on being closed, nears a perpendicular position it comes in contact with the punch-tool, which it forces through the metal. As the vise is reopened 60 spring *e* carries the punch-tool back to its first position. The action of the shears is effected in a similar manner, except that they are operated both ways by the vise and have no independent motion of their own.

65 *h* represents a slot in the vise-leg, through which the punch-chips escape.

The form and size of tool *b* may be variously changed, and clamp G *g* modified to conform thereto.

70 I claim—

1. The combination, with vise A and support D, of guide *d*, spring *e*, and punch-tool *b*, as and for the purpose set forth.

2. Slot *c* in guide *d*, in combination with bolt *e* and support D, as and for the purpose set forth.

3. The combination, with adjustable guide *d*, spring *e*, and support D, of clamp G, screw *i*, and block *g*, as and for the purpose set forth.

80 JACOB A. PAINTER.
